UNITED STATES PATENT OFFICE.

WALTER P. MURPHY, OF CHICAGO, ILLINOIS.

CAR-ROOF.

1,182,196.

Specification of Letters Patent.

Patented May 9, 1916.

Application filed January 5, 1914. Serial No. 810,404.

To all whom it may concern:

Be it known that I, WALTER P. MURPHY, a citizen of the United States, and a resident of the city of Chicago, in the county 5 of Cook and State of Illinois, have invented a new and useful Improvement in Car-Roofs, of which the following is a specification.

This invention relates particularly to 10 freight car roofs of the type made of heavy gage metal roof-plates supported on a skeleton roof substructure composed of carlines and purlins, although it is applicable to roof substructures having no purlins, and to 15 lighter sheet metal roofs having roof sheets supported on roof sheathing boards.

This invention is an improvement in 20 roofs of the type shown in my Patent No. 1,139,363, dated May 11, 1915.

Among the principal objects of my 25 invention are to make a water-tight car roof of substantial construction which will withstand hard service and will not require repairing; to retain the metal plates which 30 form the roof in position; and also permit these plates to have a limited amount of movement relative to the roof substructure; to provide an improved form of construction in which any water that may happen 35 to leak through any of the seams between the roof plates will be guided down to the eaves and not be allowed to enter the car.

Other objects of the invention relate to 40 the detail construction of the roof, as will 35 appear more fully hereinafter.

The invention consists in the construction 45 and in the arrangement and combination of parts hereinafter more fully set forth. In general, my invention comprises a metal 50 roof formed of overlapped roof-plates which extend from eaves to eaves and are secured together by being riveted along their meeting edges. The roof-plates are supported upon a skeleton roof frame work 55 and are secured to this frame work near the ridge. At the eaves, the roof-plates are held down by a fastening which permits them to have a limited amount of movement 60 longitudinally of the car. By reason of 65 this construction, as the car weaves and racks in service, the seams of the roof will not be torn or injured because the roof-plates are fixedly secured to the substructure at

the ridge only and are free to adjust themselves to the different positions which the 55 parts of the substructure may take.

In the drawings, which form part of this 60 specification, and in which like reference characters designate like parts in the several views, Figure 1 is a vertical section through the upper part of a car showing a roof embodying my invention applied thereto; Fig. 2 is a plan view of a portion of my car roof with part of a roof sheet broken away; Fig. 3 is a cross-section on a 65 line 3—3 of Fig. 1 drawn on a larger scale; Fig. 4 is a side elevation of a portion of the eaves edge of the roof at a seam showing the end seam cap in position; Fig. 5 is a cross-section through the eaves of the 70 car on a line 5—5 of Fig. 4; Fig. 6 is a view similar to Fig. 4 with the seam cap removed; Fig. 7 is a cross section through the ridge of the car on a line 7—7 of Fig. 2 drawn on a larger scale; Fig. 8 is a perspective view of the carline; Fig. 9 is a perspective view of the running board saddle; Fig. 10 is a cross-section of the carline showing a modified form of riveted roof-plate seam; Fig. 11 is a side elevation of a portion of 80 the eaves edge of the roof at a seam showing the modified construction, the seam cap being partly broken away; and Fig. 12 is a cross-section on a line 12—12 of Fig. 11.

Referring to the drawings, particularly 85 Figs. 1 to 9, the car shown therein comprises side frame members 11, to which are attached the car siding 12. The side plates 13, which extend lengthwise of the car along the tops of the sides thereof, are made 90 of metal bars of a Z cross-section. Each of these side plates 13 is disposed so that the middle web is vertical, the top flange faces in, and the bottom flange faces out. The carlines 14 are substantially inverted T- 95 shape in cross-section and are arranged parallel to each other transversely of the car and are spaced about four feet apart. The carlines 14 are placed so that their horizontal flanges 15 are at the bottom and their central webs 16 extend upward. The carlines 14 are curved upward in the middle 100 in the arc of a circle and their ends are riveted to the top flanges of the side plates 13. The horizontal flanges 15 of the carlines 105 are bent up along a line intermediate

their edges to provide a trough 17 on each side of the central web extending lengthwise of the carline. The troughs 17 catch the drip through the joints between the roof plates and convey it to the eaves. At the ends of the carlines, the troughs 17 are widened to afford space for the rivets which secure the carlines to the side plates. The horizontal flanges of the carlines support the ends of purlins 18 which are securely riveted thereto.

The roof plates 20 are made of heavy gage metal, and are supported directly on the purlins. Each of the roof plates 20 is bent at one of its side marginal edges to form an upwardly extending flange 21 inverted U-shape in cross-section. The opposite side marginal edge of each plate 20 is bent to form an upwardly extending flange 22 inverted U-shape in cross-section, the outer edge of which is extended below the plane of the plate to form a drip edge 23. The side marginal flanges 21 and 22 of adjacent plates are overlapped and fastened together by rivets 24 to form arched seams. The rivets 24 are placed in a line a few inches apart in the side of the seam above the drip edge 23. When the roof plates are placed in position, each of the arched seams 30 straddles a carline. A space is left between the top of each carline and the under side of the corresponding arched seam. Each of the drip edges 23 is directly above one of the troughs 17 in a carline and serves to carry any water which may leak around the rivets 24 or between the lapped portions of the plates down away from the under faces of the plates 20 to the eaves.

The ends of the roof plates at the eaves 40 are doubled under to form end flanges 25. These flanges 25 are loosely hooked into the doubled-over inner edges 26 of the flashing strips 27 which extend lengthwise of the car at the eaves. The flashing strips 27 are bent to fit closely against the outside faces of the side plates and are fastened thereto by rivets 28. The lower edges of the flashing strips 27 project over the lower flanges of the side plates 13 to form drip edges 29. These 50 drip edges 29 shed any water which may run off the roof plates clear of the sides of the car. The upper portions of the flashing strips 27 are cut at points opposite the ends of the carlines to form holes 30 to allow the water in the carline troughs 17 to drain through the flashing strips and over the eaves.

The end caps 31 are placed over the ends of the arched seams and carlines to prevent 60 any water from getting into the car at these points. These end caps 31 have aprons 32 which hang down over the lower flanges of the carlines and cover the holes 30 in the flashing strips 27. The end caps 31 are riveted to the roof plates at the top of the

arched seams. By this construction the roof plates are fastened to the roof substructure at the ridge only and the eaves edge of the roof plates are held loosely in position by the flashing strips 27. This allows the ends of the roof plates to have a certain amount of free movement at the eaves in their own plane, and permits the roof plates to accommodate themselves to the distortions of the car frame, such as 75 occur in service.

The running boards 33 are bolted to saddles 34, each of which straddles a carline and an arched seam for a short distance on each side of the ridge. Each running board saddle 34 has two pairs of depending lugs 35 stamped out of the top part near each end and bent down to embrace the underlying arched seam. At the points where these lugs 80 embrace the seam, U-shape pieces 36 are inserted under the arch of the seam straddling the top web 16 of the carline. Rivets or bolts 37 are passed through the depending lugs 35, the sides of the arched seam and the carline web to secure all of these parts 85 firmly together. In this way the weight which may be placed on the running boards is supported by the carlines.

The modified construction illustrated in Figs. 10 to 12 shows the application of my 90 construction for draining off any water which may pass through the seams of the roof to a different form of seam. In this modified construction, the roof plates 38 have their marginal portions formed with 100 upstanding flanges 39, U-shape in cross-section, and similar to the flanges 21 and 22 of the roof plates 20 in the preferred form. One of the marginal flanges 39 is extended to form a drip edge 40. The carlines 14' 105 are made the same as the carlines 14. Each of the overlapped flanges 39 are fastened to the vertical web of a carline 14' by a row of rivets 41 passing through the flanges of the carlines.

On each side of the car the roof plates 38 extend a short distance beyond the outer edge of the top flange of the side plate 13', and are bent downward to form drip flanges 42. Flashing strips 43, having drip edges 115 44, are fastened by rivets 45 to the outer sides of the side plates 13'. The inner edge 46 of each flashing strip 43 is bent and extended underneath the drip flange 42 and the body of the corresponding roof plate 38. 120

An end cap 47 is placed over the end of each seam and is fastened to the seam and the carline by a through rivet 48. Each end cap 47 has an apron 49 which hangs down over the lower flange of the carline and is fastened firmly to the side plate by rivets 50. The upper portions of the flashing strips 43 opposite the ends of the carlines are cut away to allow the carline troughs 17 to drain off the eaves. 125

Obviously, my device admits of considerable modification without departing from my invention, and therefore I do not wish to be limited to the specific construction shown and described.

5 What I claim is:

1. A metal car roof comprising roof plates extending from eaves to eaves and riveted together along their side margins, 10 said roof being supported on a skeleton frame to which it is rigidly fastened only near the ridge.

2. A metal car roof comprising roof plates supported on a skeleton frame and 15 extending from eaves to eaves, riveted joints connecting said roof plates along their side margins, and means at the ridge for retaining said roof plates in central alinement, said roof plates having a limited amount of 20 play on each side of the ridge relatively to said frame.

3. A metal car roof comprising roof plates fixed together throughout their length along their side margins from eaves to eaves 25 and supported on a skeleton frame, means for securing said roof to said frame at the ridge, said roof being free on each side of said ridge to move relatively to said frame.

4. A car roof construction comprising a 30 skeleton frame comprising carlines, roof plates having inverted U-shaped flanges along their side margins, said flanges of adjacent plates being lapped and riveted and forming arched seams, said arched seams 35 being spaced out of contact with said carlines, and means at the ridge for securing said arched seams to said carlines.

5. A metal car roof comprising roof plates having inverted U-shaped flanges 40 along their side margins, said flanges of adjacent roof plates being lapped and forming arched seams, the inner flange of each seam extending below the plane of the roof plates and constituting a drip edge, and rivets 45 through the lapped flanges of each seam above said drip edge.

6. A car roof construction comprising carlines having vertical webs, roof plates having inverted U-shaped flanges along 50 their side margins, said flanges of adjacent plates being lapped and riveted and forming arched seams, said seams straddling said carline webs and being spaced out of contact with said carlines.

55 7. A car roof construction comprising carlines having upstanding webs, roof plates having their side margins riveted together, said roof plates being spaced out of contact with said carlines, means for securing said 60 roof plates to said carlines at the ridge, and means for loosely securing the eaves ends of said roof plates.

8. A car roof construction comprising a skeleton frame having carlines, said car- 65 lines having horizontal flanges bent to form

drain channels, roof plates fastened together by riveted seams and supported on said frame, and drip edges extending below said plates for dropping water which may pass through said seams into said channels.

9. A car roof comprising roof plates having inverted U-shaped flanges along their side margins, said flanges of adjacent plates being lapped and riveted and forming arched seams, a drip edge along the bottom 70 of each seam, and means for conducting water dropped from said drip edges to the eaves of said car.

10. A car roof comprising roof plates having inverted U-shaped flanges along their side margins, said flanges of adjacent plates being lapped and forming arched seams, rivets extended through each of said lapped flanges along one of the side walls of said arched seam, and a drip edge along the bottom 75 of each of said riveted side walls.

11. A car roof construction comprising a skeleton frame having carlines, roof plates supported on said frame and fastened together by riveted seams, said carlines having troughs disposed under said seams for 80 conducting water to the eaves.

12. A car roof construction comprising a skeleton frame having carlines, roof plates supported on said frame and having 85 inverted U-shaped flanges along their side margins, said flanges of adjacent plates being lapped and riveted and forming seams which are disposed over said carlines, said carlines having troughs for conducting wa- 90 ter to the eaves.

13. A car roof construction comprising a skeleton frame having carlines, said carlines having vertical webs, roof plates supported on said frame and having their side 95 margins secured together by arched seams which straddle the webs of said carlines and are spaced out of contact therewith, and yoke members straddling the web of each carline near the ridge and supporting the 100 corresponding arched seam.

14. A car roof construction comprising a skeleton frame having carlines, said carlines having vertical webs, roof plates secured together by arched seams, which straddle 115 said webs and are spaced out of contact therewith, running-board saddles, each having two pairs of lugs embracing spaced opposite sides of said seam, yoke members straddling each of said webs and supporting 120 the corresponding arched seam, and a fastening means passed through each pair of lugs, yoke and said web and seam.

15. A car roof construction comprising side plates, carlines having troughs for con- 125 ducting water to the eaves, roof plates having their side margins secured together by seams which are disposed over said carlines, and eaves flashing strips coöperating with said roof plates to prevent water from en- 130

tering the car beneath the ends of said roof plates, said flashing strips having holes therein opposite said troughs.

16. A car roof construction comprising carlines having troughs for conducting water to the eaves, roof plates having their side margins disposed over said troughs, eaves flashing strips coöoperating with said roof plates to prevent water from entering the car underneath the ends of said roof plates, said flashing strips being cut away to form openings opposite the ends of said troughs, and end caps secured to the roof plates at the eaves and having depending aprons spaced from said flashing strips and covering the openings therein.

17. A car roof construction comprising side plates and a skeleton frame supported thereby, roof plates supported on said frame and having their eaves end portions doubled under, flashing strips of relatively stiff metal secured to said side plates, said flashing strips having their inner longitudinal edge portions extending above the said side plates and doubled over and hooked into the doubled under end portions of said roof plates, said doubled over portions constituting stiff flanges spaced above said side plates and loosely engaged with said roof plates to support and hold them down at the eaves and to prevent water from entering the car beneath the ends of said roof plates.

18. A car roof construction comprising side plates and a skeleton frame supported thereby, roof plates supported on said frame and spaced above said side plates at the eaves, flashing strips secured to said side plates and having flanges along their inner edge portions spaced above said side plates,

said flanges constituting supports for said roof plates at the eaves and coöoperating therewith to prevent water from entering the car beneath the ends of said roof plates.

19. A car roof comprising roof plates having their side margins joined by upstanding seams, and end caps secured to said roof plates and having depending aprons covering the ends of said seams, said caps being movable with said roof plates relatively to the car frame.

20. A car roof construction comprising a skeleton frame having carlines, said carlines having troughs for conducting water to the eaves, roof plates supported on said skeleton frame and having their side margins connected by seams which are disposed over said troughs, and end caps secured to said roof plates and having depending aprons covering the ends of the troughs of said carlines, said caps being movable with said roof plates relatively to said frame.

21. A car roof construction comprising side plates and a skeleton frame supported thereby, roof plates supported by said frame and having their side margins joined by upstanding seams, flashing strips secured to said side plates and coöoperating with said roof plates to hold them down loosely at the eaves, and end caps secured to said roof plates and having depending aprons covering the ends of said seams, said caps being movable with said roof plates relatively to said frame.

Signed at Chicago, Illinois, this 31st day of December, 1913.
